UNITED STATES PATENT OFFICE.

WILLIAM A. HATCHER, OF DETROIT, MICHIGAN, ASSIGNEE TO WERNICKE-HATCHER PUMP COMPANY, OF GRAND RAPIDS, MICHIGAN, A CORPORATION OF MICHIGAN.

ROTARY PUMP.

Application filed February 19, 1921. Serial No. 446,471.

To all whom it may concern:

Be it known that I, WILLIAM A. HATCHER, a citizen of the United States, residing at Detroit, county of Wayne, State of Michigan, have invented certain new and useful improvements in Rotary Pumps, of which the following is a specification.

This invention relates to improvements in rotary pumps, and relates particularly to that class of rotary pumps in which the piston has a rotating contact with the cylinder.

The object of the invention is to provide a structure which can be operated at high speed, in which the parts will be balanced, and in which the packing is effectively maintained.

Objects which pertain to details and economies of construction and operation will definitely appear from the detailed description to follow.

I accomplish the objects of the invention by the devices and means described in the following specification. The invention is clearly defined and pointed out in the claims.

Structures which are preferred embodiments of my invention are fully illustrated in the accompanying drawing, forming a part of this specification, in which:

Fig. I is a side elevation view of a double cylinder pump embodying the features of my invention.

Fig. II is an enlarged transverse detail sectional view taken on the irregular line 2-2 of Fig. I and Fig. III.

Fig. III is an enlarged detail sectional view taken on the angularly irregular line 3-3 of Fig. II.

Fig. IV is a detail sectional view similar to that appearing in Fig. III of a single cylinder pump.

In the drawing the sectional views are taken looking in the direction of the little arrows at the ends of the section lines, and similar numerals of reference refer to similar parts throughout the several views.

Considering the numbered parts of the drawing, the double cylinder 1 is supported on a suitable base 2 and has connected thereto the intake 41 having the port 42 opening into the cylinder and discharge port 43 delivering into the discharge chamber 44.

The two halves of the pump are precisely identical in these particulars. The cylinder 1 is provided with heads 3 and 4. On the head 3 is a stuffing box 5 in which revolves

the driving crank shaft 5 which extends into a supporting bearing hub 6 in the cylinder head 4. Roller bearings 7 and 8 are interposed to support the ends of the crank shaft, which is provided with two oppositely disposed throws 9 and 10 turning in roller bearings 9' and 10' respectively.

A partition, comprising plates 11 and 12, divides the cylinder into two parts. The plates are recessed to accommodate the crank shaft at the center and to receive the shafts 13 of the auxiliary cranks which auxiliary cranks are supported in roller bearings 14.

Cylindrical pistons 15 and 16 are provided and are carried around in rolling contact with the piston by the cranks 9 and 10 respectively. These are maintained in parallelism by the pair of auxiliary cranks 13, the crank pins 18 and 19 of which are disposed parallel with the main crank and parallel to each other to maintain the proper relative movement of the said pistons and cylinders.

The partition plates 11 and 12 are retained together by bolts not shown. The cross block 22 having a retaining screw 23 and pin 24 for filling up flat spot in the rotor case or cylinder at the partition.

A sliding vane 25, like the vane appearing in my concurrent patent application, Serial No. 446,469, filed Feb. 19, 1921, is disposed in a radial recess 25' in each of the said cylindrical pistons. The vane is provided with lateral projections 27 engaging in transverse slots 28 in the said piston head. As the various crank throws between these pistons are oppositely disposed, it will be seen that one piston counterbalances the other and consequently a perfectly balanced pump is secured, notwithstanding that the revolving parts are eccentrically disposed.

I show a single piston pump operating on the same principle in Fig. IV. There is of course only a single crank throw there, which I have shown divided into parts, 31, 32, which telescope and are splined or keyed together. The crank shaft is provided with ball bearings 29 and 30, and the main crank pin is provided with roller bearings 33. The auxiliary crank 34 has its pin 35 provided with roller bearings 36 and the pin 37 which engages the piston is provided with a roller bearing 38. Packing rings 39 and 40 are provided between the piston and the cylinder heads. The other parts are substan-

tially counterparts of those appearing in the structure illustrated in Fig. III and are numbered with corresponding numerals.

Having thus described my invention what I claim as new and desire to secure by Letters Patent is:

- 5 1. In a rotary pump the combination of a double cylinder supported upon a base provided with intake and discharge chambers and ports, a crank shaft axially disposed within the said cylinder and with oppositely disposed crank throws for each said cylinder, a cylindrical piston of less diameter than the said cylinders disposed within each 10 cylinder and in contact therewith, supported upon each of said crank throws, auxiliary parallel cranks supported between said cylinders with oppositely disposed crank pins engaging suitable bearings in the said piston and disposed parallel to the main cranks, and a radially disposed sliding vane in a recess in each piston and bearing between said intake and discharge ports, with means for maintaining it in contact with 15 said cylinder, coacting as specified.
- 20 2. In a rotary pump the combination of a cylinder with a suitable support therefor, provided with intake and discharge ports, a crank shaft axially disposed to the said cylinder and with a crank and crank pin within the cylinder, a cylindrical piston of less diameter than said cylinder disposed in contact with the said cylinder and journalled upon the said crank pin, auxiliary means connecting the said piston and cylinder to maintain the piston 25 in parallel relation thereto during rotation, an intake and an exhaust port, and a vane means between said intake and exhaust, as described.
- 30 3. In a rotary pump the combination of a cylinder with a suitable support therefor, provided with intake and discharge ports, a crank shaft axially disposed to the said cylinder and with a crank and crank pin within the cylinder, a cylindrical piston of less diameter than said cylinder disposed in contact with the said cylinder and journalled upon the said crank pin, auxiliary means connecting the said piston and cylinder to maintain the piston 35 in parallel relation thereto during rotation, an intake and an exhaust port, and a vane means between said intake and exhaust, as described.
- 40 4. In a rotary pump the combination of a cylinder with a suitable support therefor, provided with intake and discharge ports, a crank shaft axially disposed to the said cylinder and with a crank and crank pin within the cylinder, a cylindrical piston of less diameter than said cylinder disposed in contact with the said cylinder and journalled upon the said crank pin, auxiliary parallel cranks disposed between said cylinder and said piston and parallel to the main crank, and a radially disposed sliding vane between the intake and discharge, coacting as specified.
- 45 5. In a rotary pump the combination of a cylinder with a support therefor, a crank shaft axially disposed to the said cylinder and with a crank pin within the cylinder, a cylindrical piston of less diameter than said cylinder disposed in contact with the said cylinder and journalled upon the said crank pin, auxiliary means connecting the said piston and cylinder to maintain the piston 50 in parallel relation thereto during rotation, an intake and an exhaust port, and a vane means between said intake and exhaust, as described.

inder and with a crank and crank pin within the cylinder, a cylindrical piston of less diameter than said cylinder disposed in contact with the said cylinder and journalled upon the said crank pin, auxiliary parallel cranks disposed between said cylinder and

45

said piston and parallel to the main crank, and a vane means between said piston and cylinder, coacting as specified.

50 4. In a rotary pump the combination of a cylinder with a support therefor, provided with intake and discharge ports, a crank shaft axially disposed to the said cylinder and with a crank pin within the cylinder, a cylindrical piston of less diameter than said cylinder disposed in contact with the said cylinder and journalled upon the said crank pin, auxiliary means connecting the said piston and cylinder to maintain the piston 55 in parallel relation thereto during rotation, an intake and an exhaust port, and a vane means between said intake and exhaust, as described.

55 5. In a rotary pump the combination of a cylinder with a support therefor, a crank shaft axially disposed to the said cylinder and with a crank pin within the cylinder, a cylindrical piston of less diameter than said cylinder disposed in contact with the said cylinder and journalled upon the said crank pin, auxiliary means connecting the said piston and cylinder to maintain the piston 60 in parallel relation thereto during rotation, an intake and an exhaust port, and a vane means between said intake and exhaust, as described.

65 6. In witness whereof, I have hereunto set my hand and seal in the presence of two witnesses.

WILLIAM A. HATCHER. [L.S.]
